US00D522848S

(12) **United States Design Patent** (10) **Patent No.:** **US D522,848 S**
(45) **Date of Patent:** **** Jun. 13, 2006**

(54) **SHELVING COMPONENT**

(75) Inventor: **John Richard Nawrocki**, Ocala, FL
(US)

(73) Assignee: **Clairson, Inc.**, Newark, DE (US)

(**) Term: **14 Years**

(21) Appl. No.: **29/239,194**

(22) Filed: **Sep. 27, 2005**

Related U.S. Application Data

(63) Continuation of application No. 11/231,381, filed on Sep. 21, 2005, which is a continuation-in-part of application No. 11/194,849, filed on Aug. 1, 2005, which is a division of application No. 10/657,855, filed on Sep. 9, 2003, now Pat. No. 6,953,176, which is a continuation of application No. 09/436,363, filed on Nov. 9, 1999, now Pat. No. 6,669,154.

(51) **LOC (8) Cl.** **08-05**

(52) **U.S. Cl.** **D8/381**

(58) **Field of Classification Search** D8/381,
D8/363; 248/235, 237, 243, 245, 247

See application file for complete search history.

U.S. Appl. No. 60/434,470, filed Dec. 18, 2002, Costa, et al.

Primary Examiner—Holly H. Bayham

(74) *Attorney, Agent, or Firm*—Harness, Dickey & Pierce, P.L.C.

(57) **CLAIM**

The ornamental design for a shelving component, as shown and described.

DESCRIPTION

FIG. 1 is a perspective view of a shelving component, showing my new design;

FIG. 2 is a back perspective view of the shelving component shown in FIG. 1;

FIG. 3 is a lower back perspective view of the shelving component shown in FIG. 1;

FIG. 4 is a left side elevation view of the shelving component shown in FIG. 1;

FIG. 5 is a right side elevation view of the shelving component shown in FIG. 1;

FIG. 6 is a back elevation view of the shelving component shown in FIG. 1;

FIG. 7 is a front elevation view of the shelving component shown in FIG. 1;

FIG. 8 is a bottom plan view of the shelving component shown in FIG. 1;

FIG. 9 is a top plan view of the shelving component shown in FIG. 1; and,

FIG. 10 is a perspective view of the shelving component shown in FIG. 1 engaged with a track and supporting a wire ventilated support structure.

The details shown in broken lines are for illustrative purposes only and form no part of the claimed design.

1 Claim, 5 Drawing Sheets
